[57] CLAIM

The ornamental design for electronic component package, as shown and described.

DESCRIPTION

FIG. 1 is a perspective view of an electronic component package in accordance with the present design;
FIG. 2 is a front elevational view thereof;
FIG. 3 is a back elevational view thereof;
FIG. 4 is a top plan view thereof;
FIG. 5 is a bottom plan view thereof;
FIG. 6 is a right side elevational view thereof;
FIG. 7 is a left side elevational view thereof; and
FIG. 8 is a cross-sectional view of the electronic component package taken along line 8—8 of FIG. 2.
The package is understood to have an indeterminate length.
